UNITED STATES PATENT OFFICE

135,774

DESIGN FOR A TOY GUN

Samuel L. Leider, New York, N. Y.

Application April 26, 1943, Serial No. 110,045

Term of patent 7 years

To all whom it may concern:

Be it known that I, Samuel L. Leider, a citizen of the United States, resident of the Borough of Queens, county of Queens, city and State of New York, have invented a new, original, and ornamental Design for a Toy Gun, of which the following is a specification, reference being had to the accompanying drawing, forming part thereof.

I claim:

The ornamental design for a toy gun, substantially as shown.

SAMUEL L. LEIDER.
